[57] CLAIM

The ornamental design for a key chain box, as shown and described.

DESCRIPTION

FIG. 1 is a top, left perspective view of a key chain box showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top, left perspective view of a second embodiment of FIG. 1, the only difference being acceptance of alternate key chain tab configurations;

FIG. 9 is a top plan view of FIG. 8;

FIG. 10 is a bottom plan view of FIG. 8;

FIG. 11 is a front elevational view of FIG. 8;

FIG. 12 is a rear elevational view of FIG. 8;

FIG. 13 is a left side elevational view of FIG. 8;

FIG. 14 is a right side elevational of FIG. 8;

FIG. 15 is a top, left perspective view of a third embodiment of FIG. 1, the only differences being an integral hinge and acceptance of alternate key chain tab configurations;

FIG. 16 is a top plan view of FIG. 15;

FIG. 17 is a bottom plan view of FIG. 15;

FIG. 18 is a front elevational view of FIG. 15;

FIG. 19 is a rear elevational view of FIG. 15;

FIG. 20 is a left side elevational view of FIG. 15; and.

FIG. 21 is a right side elevational view of FIG. 15.

The broken line showing of a chain in FIGS. 1, 8 and 15 is for illustrative purposes only and forms no part of the claimed design. Further, the broken line shown the chain tab of FIGS. 8-12 and 15-18 is for illustrative purposes and forms no part of the claimed design for the alternate embodiment.
